UNITED STATES PATENT OFFICE

CHARLES B. KENNEDYE, OF UNIVERSITY CITY, MISSOURI, ASSIGNOR TO THE KENNEDYE CORPORATION, OF WILMINGTON, DELAWARE, A CORPORATION OF DELAWARE

WELL-DRILLING TOOL

Continuation of application Serial No. 31,058, filed May 18, 1925. This application filed November 9, 1929. Serial No. 406,176.

This application is a continuation of my co-pending application, Serial No. 31,058, filed May 18, 1925.

Many difficulties have been experienced in drilling wells of relatively great depth. For instance, in drilling through formations of varying degrees of hardness, the bits become dull and do not drill a hole of uniform diameter. Or, a hard spot in the formation may force the drill out of vertical line, producing a "kink" in the side walls of the hole. Or, a projecting stone loosened by the drill may protrude inwardly beyond the periphery of the hole, causing the casing, when lowered into place, to stick and bind. Very frequently, proper placement of the casing is prevented because the walls of the drilled hole are neither smooth nor exactly vertical. These difficulties and conditions require that the casing be raised and withdrawn to permit reaming of the hole to proper size to allow the casing to be lowered into place. Also, the bits must be withdrawn to permit re-sharpening.

To obviate these time-consuming and expensive steps, I have devised, and my invention has for a primary object, the provision of a well-drilling tool comprising drilling and reaming bits of novel construction for the economical and efficient accomplishment of the dual operations of drilling and reaming at the same time.

My invention has for another object the provision of a tool of the type stated comprising a body or stock and a plurality of detachable bits that may be readily and conveniently removed and replaced. The stock and bits are so constructed that the bits, when in operative position, are firmly and securely held against accidental displacement.

My invention has for a still further object the provision of a tool of such construction that water under pressure is discharged directly upon the cutting edges of the bits and upon the bottom of the hole being drilled, with the result that the drilling of the well is greatly facilitated.

My invention has for a still further object the improvement of rotary well drilling tools.

In the accompanying drawings, Fig. 1 is

a view, partly in elevation and partly in longitudinal section, of a rotary well-drilling tool embodying my invention.

Fig. 2 is an elevational view of the tool taken at right angles to the view illustrated in Fig. 1.

Fig. 3 is an inverted plan or bottom view of the tool.

Fig. 4 is a detail sectional view of the tool taken on the line 4-4 of Fig. 3.

Fig. 5 is an elevational view of the tool of my invention equipped with drilling-bits of the reversible type shown in Fig. 6.

Fig. 6 is an elevational view of a modified type of detachable drilling-bit forming part of the tool.

Referring more in detail to the drawings, A designates the body of the tool, which is constructed of suitable metal and is of suitable weight and dimensions. Body A has preferably its greatest diameter at a point 1 intermediate its ends. To facilitate drilling operations, the lower end is cut-away upon opposite sides and provided with opposed faces 2, sinuous in surface contour transversely of the stock in simulation of the tail of a fish, as best seen in Figs. 1 and 2.

From intermediate point 1 the bit-body A is diametrically reduced to provide an annular shoulder 4, and a threaded extension 5 for convenient engagement with the drill-tubing (not shown).

Formed in and opening to the base and to opposite sides of the body A, is a pair of oppositely disposed slots 6, which may be disposed obliquely to the longitudinal axis of body A.

Also formed in and opening to the base and to opposite sides of the body A is a pair of longitudinal slots 7, which may be radially offset relative to the longitudinal axis of body A.

The slots 6 and 7 on each side of body A may be disposed in pairs. At its base stock A is so cut away that the slots 6 and 7 of a pair are in open communication, the upper wall 8 of each slot 7 being disposed in body A at a suitable distance from the upper wall 9 of its companion slot 6.

The stock A is preferably equipped with two sets of slots 6 and 7, and their accommodated bits, although it is to be understood

stock A may be formed to include a greater or lesser number of sets of slots and bits. Inasmuch, however, as the slots and bits are of similar construction, but one pair will be here specifically described.

5 Formed in one wall of each slot 6 and extending transversely of body A is a recess 10 opening at its outer end to the surface of body A and at its inner end being in semi-cooperative alignment with a threaded screw-seat 11 formed in the end wall of the slot, as best seen in Fig. 1. Also formed in a wall of slot 7 and extending longitudinally of body A from its lower end to beyond the plane of the wall 8 of companion slot 6 is a recess 12. Also formed in the opposite wall of slot 7 and extending in parallelism with recess 12 longitudinally and upwardly of stock A for a suitable distance from wall 8 of companion slot 6, is a recess 13 closed at its upper end and opening at its lower end to wall 8.

10 Adapted to removably fit in the cross-slots 6, are drilling-bits B. Each drilling bit B includes a body 14 approximately rectangular in configuration and of dimensions to fit within slot 6, and an angularly projecting lower cutting end 15 whose cutting edge is gradually arcuated at the lower inner corner, as shown at 16. Formed in one of the outer surfaces of bit-body 14, is a transverse recess 17 for bit-retaining cooperation with the recess 10 of stock A; and formed in the inner surface of bit-body 14 is a longitudinal recess 18 with which, when bit B is in working position in stock A, the stock-recess 13 forms an aligning continuation.

15 Similarly adapted to slidably fit in the longitudinal slots 7 are individual reaming-bits C, each comprising a substantially oblong-rectangular body 19 which may have its greatest thickness at approximately its longitudinal center and which may then oppositely taper in thickness towards its ends, as best seen in Figs. 2, 4 and 6. At its opposite ends the bit C is preferably bifurcated and provided with drilling teeth 20. The bit C and its accommodating slot 7 are of such relative dimensions that, when in working position in stock A, bit C fits endwise in the slot and projects outwardly beyond the plane of the adjacent face of stock A. I may here state that the bits B and C and their accommodating slots 6 and 7 are of such relative dimensions that normally the teeth 20 are disposed in substantially the same cutting plane as the cutting edge of the drill-bit B. Formed longitudinally in the opposite side faces of the bit C are parallel recesses 21, one of which is adapted for bit-locking co-operation with the drill-bit recess 18 and its stock-recess continuation 13 and the other of which is adapted for co-operation for a like purpose with the stock-recess 12.

20 In use and operation, a rib or ribs 23 may be placed in the recesses 21 of reaming bit C

and said bit then forced upwardly into the stock to fit in the head in a slot 7, the rib or ribs registering with the recesses 12 and 13 in the wall of the slot 7. The drilling bit B is then inserted upwardly to fit in the head in a slot 6, and a pin 22 fitted end-wise in the transverse recesses 10 and 17, the pin 22 being threaded at its end into the socket 11, as best seen in Fig. 1. It will be understood that the rib 23 registers with the recess 18 in the drilling bit B.

25 The rib or ribs 23 thus form projectives in the nature of locking-ribs on the reamer C, and thus effectively positively retain both the drill-bit B and the reamer-bit C from side-wise displacement.

30 It will be obvious, therefore, that upon removal of pin 22, the bit B may be removed, and on the application of proper force on the upper end of reamer C, the latter may be driven downwardly, and either or both bits repaired or replaced. It will be evident that, while I here show the ribs 23 as separate or loose from the bit C, such ribs may, if desired, be integral with the reamer C. When so locked in the body A, the angular cutting ends 15 of bits B are projected in the direction of rotation of the body with their rounded lower corners 16 inwardly presented relative to the stock, their longitudinal axis being parallel, corresponding to the obliquely disposed arrangement of their accommodating slots 6 and their cutting ends 15, completing the resemblance of body A and its bits B to the tail of a fish. Normally, the drilling prongs 20 of reamers C are substantially 35 on the same horizontal cutting plane as the cutting edges of the drilling bits B, being disposed in the rear of the cutting edges of drilling bits B, functioning to materially assist 40 the bits B in effective drilling operations. In practice, the bits B at their outer sides extend slightly beyond the arcuated sidefaces of the reaming-bits C and form straight lines parallel with the longitudinal axis of the stock 45 A. By this construction, the diameter of the hole being drilled is uniformly maintained. The reamers C efficiently function in the rotary actuations of stock A in smoothing and straightening the walls of the hole being 50 drilled.

55 Thus, by means of my new tool, both reaming and drilling operations may be accomplished at the same time. Both reaming and drilling bits may be inexpensively repaired or replaced, and I may add that my new tool has been found exceedingly efficient in use and operation, is relatively inexpensive in maintenance, facilitates and largely reduces the cost of well drilling, and accomplishes fully 60 the objects and purposes hereinbefore stated.

65 It will be evident further that, when the prongs 20 at one end of a reamer C become worn, the reamer may be reversed to present its other end-prongs for drilling operations 70

or its other side face for reaming operations. And for a like purpose I may selectively employ drilling bits or the type B' shown specifically in Figs. 5 and 6, which in configuration are substantially similar to bit B, except that its so-called body-portion 14' and its cutting-end portion 15' are duplicates, the body 14' having a like cutting edge arcuated at one corner, as at 16', and the cutting-end portion 15' having both a pin-accommodating transverse recess 17' and a rib-accommodating longitudinal recess 18', whereby, when that portion of the rib presented for drilling operations becomes worn, the bit may be reversed to present its other portion for drilling operations.

Formed in approximately the longitudinal center of the body A is a water duct 24, which extends from the upper end of stock A, where it is adapted for open communication with the inlet channel of the drill-tubing (not shown), to a point, as at 25, adjacent the slots 6, where channel 24 divides into branch-ducts 26, opening upon the outer surface of stock A to form surface grooves for conducting the discharging water more or less directly upon, and thereby flushing and keeping clean, the drilling bits B. It will be understood that water, under considerable head, is forced along the cutting surfaces of the drilling bits B and upon the bottom of the hole being drilled in such a manner as not only to remove loose matter from the particular well, but also to keep the bits B substantially entirely free from accumulated dirt, stone-dust and the like.

I claim as my invention:

1. A rotary well drilling tool, including in combination, a head having end slots, primary drilling bits removably carried in said end slots and extending outwardly beyond the side of the head to cut a hole of predetermined size, longitudinal slots in the sides of the head communicating with the end slots, elongated reaming bits each having an elongated reaming side projecting beyond the side of the head and lying in a plane parallel to the plane of the head removably mounted in the longitudinal slots, said reaming bits being disposed immediately adjacent the primary drilling bits, and having cutting edges on their lower ends acting as secondary drilling bits.

2. A rotary well drilling tool, including in combination, a head having end slots, of primary drilling bits removably carried in said end slots and extending outwardly beyond the side of the head to cut a hole of predetermined size, longitudinal slots in the sides of the head communicating with the end slots, elongated reaming bits each having an elongated reaming side projecting beyond the side of the head and lying in a plane parallel to the plane of the head removably mounted

in the longitudinal slots, said reaming bits being disposed immediately adjacent the primary drilling bits, and having cutting edges on their lower ends acting as secondary drilling bits, and means cooperating between the reaming bits and head for preventing accidental side-wise displacement.

3. A rotary well drilling tool, including in combination, a head having end slots and extending outwardly beyond the side of the head to cut a hole of predetermined size, of primary drilling bits removably carried in said end slots, longitudinal slots in the sides of the head communicating with the end slots, elongated reaming bits having an elongated reaming side projecting beyond the side of the head and lying in a plane parallel to the plane of the head and removably mounted in the longitudinal slots, said reaming bits being disposed immediately in the rear of the primary drilling bits, and having cutting ends acting as secondary drilling bits, and means cooperating between the drilling bits and the head for preventing accidental longitudinal displacement of the former.

4. A rotary well drilling tool comprising in combination, a supporting head provided with a longitudinal slot and a separate but communicating transverse slot opening respectively to a side and to the base of the head, a reamer having a body portion and a reaming edge adapted to have removable cooperative engagement with said head in said longitudinal slot in such manner as to cause only a relatively small portion of said reamer, including said reaming edge, to project beyond the side wall of said head, a drilling bit also adapted to have removable cooperative engagement with said head in said transverse slot, the main surface of the drilling bit being disposed in contact with the main surface of said reamer, said drilling bit having a cutting edge projecting from the base of said head, and means associated with the reamer adapted for engagement with both the stock and the drilling bit for detachably securing said reamer and drilling bit from unintentional sidewise displacement.

5. A rotary well drilling tool comprising in combination, a supporting head having a longitudinal slot opening to a side thereof and a longitudinal recess in a wall defining said slot, a reamer disposed for removal in said slot, said reamer having means associated therewith for engaging the head at said recess for detachably securing said reamer against sidewise displacement, a transverse slot communicating with said longitudinal slot, a drilling bit removably carried in the transverse slot having a bottom cutting edge, and extending outwardly beyond the side of the head to cut a hole of predetermined size, said reamer having a cutting edge disposed at the bottom portion thereof, and adapted

to cut in the same circular cutting plane as the bottom cutting edge of the drilling bit.

6. A rotary well drilling tool comprising in combination, a supporting head having a longitudinal slot and a longitudinal recess disposed in a wall of said slot, a reamer disposed for removal in said slot, and a locking rib cooperatively associated with said reamer for engagement with said head at said recess for detachably securing the reamer against sidewise displacement, a transverse slot communicating with said longitudinal slot, a drilling bit removably carried in the transverse slot having a bottom cutting edge, and extending outwardly beyond the side of the head to cut a hole of predetermined size, said reamer having a cutting edge disposed at the bottom portion thereof, and adapted to cut in the same circular cutting plane as the bottom cutting edge of the drilling bit.

7. A rotary well drilling tool comprising in combination, a supporting head having a longitudinal slot opening to the side thereof and a longitudinal recess disposed in a wall of said slot, a reamer comprising a body portion and an elongated reaming surface adapted to have removable cooperative engagement with said head in said longitudinal slot in such manner as to cause only a relatively small portion of said reamer, including said reaming surface, to project beyond the side wall of said head, and a rib projection associated with said reamer adapted to have cooperative locking engagement with the head in said recess for detachably securing the reamer against unintentional sidewise displacement, a transverse slot communicating with said longitudinal slot, a drilling bit removably carried in the transverse slot having a bottom cutting edge, and extending outwardly beyond the side of the head to cut a hole of predetermined size, said reamer having a cutting edge disposed at the bottom portion thereof, and adapted to cut in the same circular cutting plane as the bottom cutting edge of the drilling bit.

8. A rotary well drilling tool comprising in combination, a supporting head having communicating transverse and longitudinal slots and a recess in a wall of the longitudinal slot, a drilling bit disposed for removal in said transverse slot, a reamer having a body portion and an elongated reaming surface adapted to have removable cooperative engagement with said head in said longitudinal slot in such manner as to cause a relatively small portion of said reamer, including said reaming surface to project beyond the side wall of said head, a main surface of the drilling bit being disposed in contact with a main surface of the reaming bit, and means comprising a locking rib cooperatively associated with a surface of said reamer adapted for engagement with said recess for securing

said reamer against accidental sidewise displacement.

9. A rotary well drilling tool comprising in combination, a supporting head, a primary cutting blade mounted in said head and projecting therebelow adapted to cut a hole of predetermined size, and a secondary blade mounted in said head and projecting therebelow adapted to cut on the bottom of the hole in the same circular cutting plane as the primary blade and simultaneously ream the side of the hole to gauge, a main surface of the primary cutting blade being disposed in contact with a main surface of the secondary blade.

10. A rotary well drilling tool comprising in combination, a supporting head, a primary cutting blade detachably mounted in said head and projecting therebelow adapted to cut a hole of predetermined size, and a secondary blade detachably mounted in said head and projecting therebelow, adapted to cut on the bottom of the hole in the same circular cutting plane as the primary blade and simultaneously ream the hole to gauge, a main surface of the primary cutting blade being disposed in contact with a main surface of the secondary blade.

11. A rotary well drilling tool comprising in combination, a supporting head having a longitudinal slot opening to a side thereof and a communicating transverse slot opening to the base thereof, a primary cutting blade detachably mounted in said transverse slot and projecting below said head adapted to cut a hole of predetermined size, and a separate blade detachably mounted in said longitudinal slot and projecting beyond the side wall and also below the base of said head adapted to cut on the bottom of the hole in the same circular cutting plane as the primary blade and simultaneously ream the hole to gauge a main surface of the primary cutting blade being disposed in contact with a main surface of the said separate blade.

12. A rotary well drilling tool comprising in combination, a supporting head, a primary cutting blade detachably mounted in said head and projecting therebelow adapted to cut a hole of predetermined size, and a secondary blade detachably mounted in said head and projecting therebelow, adapted to cut on the bottom of the hole in the same circular cutting plane as the primary blade and simultaneously ream the hole to gauge, said primary cutting blade having cooperative engagement with said secondary blade to lock said secondary blade in said head, whereby said primary blade must be removed from said head before said secondary blade can be removed from said head.

13. A rotary well drilling tool comprising in combination, a head, a primary drilling blade removably mounted in said head, a second blade having an elongated reaming side

and a cutting edge, said second blade projecting beyond the side of said head and lying in a plane parallel to the axis of the head, said second blade being disposed immediately adjacent the primary blade whereby the lower cutting edge acts as a secondary cutting blade, a main face of the primary drilling blade being disposed in contact with the main face of the second blade.

14. A rotary well drilling tool comprising in combination, a supporting head provided with a longitudinal slot and a separate but communicating transverse slot both opening respectively to a side and to the base of the head, said longitudinal slot being closed at its upper end, a reamer having a body portion and a reaming surface adapted to have removable cooperative engagement with said head and said longitudinal slot in such manner as to permit only a relatively small portion of said reamer, including the reaming surface thereof to project beyond the side wall of said head, a drilling bit also adapted to have removable cooperative engagement with said head in said transverse slot, said drilling bit having a cutting edge projecting from the base of said head, and means associated with the reamer adapted for engagement with both the head and the drilling bit for detachably securing said reamer from unintentional sidewise displacement.

15. A rotary well drilling tool comprising in combination, a supporting head provided with a longitudinal slot and a separate but communicating transverse slot both opening respectively to a side and to the base of the head, said longitudinal slot being closed at its upper end, a reamer having a body portion and a reaming surface adapted to have removable cooperative engagement with said head and said longitudinal slot in such manner as to permit only a relatively small portion of said reamer, including the reaming surface thereof to project beyond the side wall of said head, a drilling bit also adapted to have removable cooperative engagement with said head in said transverse slot, said drilling bit having a cutting edge projecting from the base of said head, and means associated with the reamer adapted for engagement with both the head and the drilling bit for detachably securing said reamer from unintentional sidewise displacement, said reamer being insertable in said head only by longitudinally sliding said reamer upwardly in said head, said reamer being cut away to contact and be supported by the drilling bit whereby the drilling bit must be removed from the head before the reamer can be removed.

16. A rotary well drilling tool comprising in combination, a supporting head provided with a longitudinal slot and a separate but communicating transverse slot both opening respectively to a side and to the base of the

head, said longitudinal slot being closed at its upper end, a reamer having a body portion and a reaming surface adapted to have removable cooperative engagement with said head and said longitudinal slot in such manner as to permit only a relatively small portion of said reamer, including the reaming surface thereof to project beyond the side wall of said head, a drilling bit also adapted to have removable cooperative engagement with said head in said transverse slot, said drilling bit having a cutting edge projecting from the base of said head, and means associated with the reamer adapted for engagement with both the head and the drilling bit for detachably securing said reamer from unintentional sidewise displacement, said reamer being insertable upwardly in said head until the upper edge of said reamer abuts against the wall closing the upper end of said longitudinal slot.

17. A rotary well drilling tool including in combination, a head having radial base slots and longitudinal side slots communicating therewith, drilling bits removably mounted in said radial slots, reaming bits removably mounted in said longitudinal slots, the outer edges of said reaming bits extending beyond the adjacent face of the head and presenting elongated reaming surfaces lying in a plane parallel to the axis of the head, said drilling bits and reaming bits projecting from the base of the head, and both having bottom cutting edges rotating in the same circular cutting plane.

18. A rotary well drilling tool including in combination a head having radial base slots and longitudinal side slots, drilling bits adapted to be removably mounted in said radial slots, reaming bits adapted to be removably mounted in said longitudinal slots, the outer edges of said reaming bits extending beyond the adjacent face of the head and presenting elongated longitudinal reaming sides lying in a plane parallel to the axis of the head, said drilling bits and reaming bits projecting from the base of the head, and both having drilling edges rotating in the same orbit, said reaming bits being mounted immediately adjacent and in contact with the drilling bits, the drilling edges of the reamers operating as secondary cutters.

19. A rotary well drilling tool including in combination a head having radial base slots and longitudinal side slots, drilling bits adapted to be removably mounted in said radial slots, reaming bits adapted to be removably mounted in said longitudinal slots, the outer edges of said reaming bits extending beyond the adjacent face of the head and presenting elongated longitudinal reaming sides lying in a plane parallel to the axis of the head, said drilling bits and reaming bits projecting from the base of the head, and both

having drilling edges rotating in the same circular cutting plane, said reaming bits being mounted immediately adjacent and in contact with the drilling bits, the drilling edges of the reamers operating as secondary cutters, said drilling bits being bent intermediate their length to provide drilling edges projecting forwardly into the path of rotation while the drilling edges of the reaming bits lie in a plane substantially parallel to the longitudinal axis of the head.

20. A rotary well drilling tool comprising in combination a supporting head provided with longitudinal slots communicating with offset transverse slots opening respectively to the sides and base of the head, reamers adapted to have removable cooperative engagement with said head in said longitudinal slots, each reamer comprising a body portion having an elongated relatively thin reaming surface projecting beyond a side wall of the supporting head, a substantial portion of each reamer being supported in and enclosed by said head, drilling bits also adapted to have removable cooperative engagement with said head in said transverse slots and disposed in contact with said reamers, said drilling bits projecting from the base of said head and having cutting edges on their lower ends, said reamers also provided with cutting edges on their lower end to simultaneously drill on the bottom of the hole being drilled by the drilling bits and so disposed as to rotate in the same circular plane as the drilling bits.

21. A rotary well drilling tool comprising in combination a supporting head provided with a longitudinal slot communicating with an offset transverse slot opening respectively to a side and to the base of the head, a reamer having a body portion and an elongated relatively thin reaming surface adapted to have removable cooperative engagement with said head in said longitudinal slot in such manner as to cause a relatively small portion of said reamer, including said reaming surface, to project beyond the side wall of said head, a drilling bit also adapted to have removable cooperative engagement with said head in said transverse slot, the main surface of which drilling bit is disposed in contact with a main surface of said reamer, said drilling bit projecting from the base of said head and having a cutting edge on its lower end, said reamer being provided with a cutting edge on its lower end to simultaneously drill on the bottom of the hole being drilled by the drilling bit and so disposed as to rotate in the same circular plane as the drilling bits.

22. A rotary well drilling tool comprising in combination a supporting head provided with longitudinal slots communicating with offset transverse slots opening respectively to the sides and base of the head, reamers

adapted to have removable cooperative engagement with said head in said longitudinal slots, each reamer comprising a body portion having an elongated relatively thin reaming surface projecting beyond a side wall of the supporting head, a substantial portion of each reamer being supported in and enclosed by said head, drilling bits also adapted to have removable cooperative engagement with said head in said transverse slots and disposed in contact with said reamers, said drilling bits having cutting edges projecting from the base of said head, each drilling bit comprising a supporting body portion adapted to be supported in and enclosed by said head and a drilling blade provided on its extreme lower edge with a substantially horizontal cutting surface of considerable area, said reamers being provided with cutting edges on their lower end to simultaneously drill on the bottom of the hole being drilled by the reaming bits and so disposed as to rotate in the same circular plane as the drilling bits.

23. A rotary well drilling tool comprising in combination a supporting head provided with longitudinal slots communicating with offset transverse slots opening respectively to the sides and base of said head, reamers adapted to have removable cooperative engagement with said head in said longitudinal slots, each reamer having a relatively small portion projecting beyond the side wall of said head, terminating in an elongated edge adapted to be presented to the formation being drilled, drilling bits also adapted to have removable cooperative engagement with said head in said transverse slots, said drilling bits having cutting edges projecting from the base of said head, said reamers being provided with cutting edges on their lower end to simultaneously drill on the bottom of the hole being drilled by the drilling bits and disposed to rotate in the same circular plane as the drilling bits.

24. A rotary well drilling tool comprising in combination a supporting head provided with longitudinal slots communicating with offset transverse slots opening respectively to the sides and base of said head, reamers adapted to have removable cooperative engagement with said head in said longitudinal slots, each reamer having a relatively small portion projecting beyond the side wall of said head, terminating in an elongated edge adapted to be presented to the formation being drilled, drilling bits also adapted to have removable cooperative engagement with said head in said transverse slots, said drilling bits having cutting edges projecting from the base of said head, said cutting edges comprising knife-like edges on the extreme lower edge of each drilling bit, said knife-like edges functioning as a horizontal cutting surface and being of considerable width,

said reamers being provided with cutting edges on their lower end to simultaneously drill on the bottom of the hole being drilled by the drilling bits and disposed to rotate in the same circular plane as the drilling bits.

⁵ In testimony whereof I affix my signature.

CHARLES B. KENNEDYE.

said reamers being provided with cutting edges on their lower end to simultaneously drill on the bottom of the hole being drilled by the drilling bits and disposed to rotate in the same circular plane as the drilling bits.
5 In testimony whereof I affix my signature.
